UNITED STATES PATENT OFFICE.

FREDERICK W. TUERK, OF CHICAGO, ILLINOIS, ASSIGNOR TO THE TUERK NOVELTY COMPANY, OF CHICAGO, ILLINOIS, A CORPORATION OF SOUTH DAKOTA.

CARBURETER.

963,187.

Specification of Letters Patent. Patented July 5, 1910.

Application filed May 15, 1909. Serial No. 496,162.

To all whom it may concern:

Be it known that I, FREDERICK W. TUERK, a citizen of the United States, and a resident of the city of Chicago, Cook county, 5 Illinois, have invented certain new and useful Improvements in Carbureters; and I do hereby declare that the following is a full, clear, and exact description of the same, reference being had to the accompanying 10 drawings, and to the letters of reference marked thereon, which form a part of this specification.

This invention relates to improvements in carbureters of that class adapted to afford 15 the mixture of air and hydro-carbon vapor fuels in explosive or internal combustion engines.

Of the various carbureters that are now 20 in commercial use, difficulty is experienced in affording complete vaporization of the hydro-carbon fluid and thorough mixture of the requisite quantity of atmospheric air therewith to insure as nearly as may be the condition of fixed gases and the more 25 nearly this may be approximated, the less difficulty is encountered in cooling the engine, and of course, much less trouble is encountered because of faulty or imperfect combustion.

30 The object of this invention is to afford first, a carbureter in which the supply of the hydro-carbon fluid may be perfectly graduated by means of the motor thereon and also in which the requisite supply of 35 air is automatically controlled to afford as nearly as may be a perfect explosive mixture.

It is an important object of the invention 40 to afford in connection therewith means for thoroughly mixing the hydro-carbon vapor with atmospheric air and delivering the same to the motor.

It is also an object of the invention to 45 afford a carbureter in which the throttle valve may be set or arranged with reference to the remaining portions of the carbureter to render the same more convenient for access than has frequently been the case.

Finally, it is an object of the invention 50 to afford an exceedingly cheap, simple and durable device of the class described, of few parts and thoroughly automatic in operation in all its parts.

The invention consists in the matters here-

inafter described and more fully pointed out and defined in the appended claims.

In the drawings: Figure 1 is a central vertical section of a carbureter embodying my invention. Fig. 2 is a section taken on line 2—2 of Fig. 1. Fig. 3 is a section taken on line 3—3 of Fig. 1. Fig. 4 is a section taken on line 4—4 of Fig. 1. Fig. 5 is a fragmentary view in elevation of the indicating adjusting head for the inlet valve. Fig. 6 is a top plan view of a device embodying my invention. Fig. 7 is a fragmentary section taken on line 7—7 of Fig. 1. Fig. 8 is a side elevation of the outlet end of the carbureter showing the throttle levers in elevation. Fig. 9 is a fragmentary detail illustrating a modification of the float feed chamber and mechanism and valve. Fig. 10 is a section on line 10—10 of Fig. 9.

As shown in the drawings: Said carbureter comprises a float feed chamber or reservoir indicated by A, integrally connected with the mixing chamber B. Said float feed chamber, as shown, comprises a bottom a, and side walls a', and a cover a'', having screw threaded engagement with the side walls. Below the bottom a, is provided an inlet chamber A', for the gasoline. For this purpose, as shown, downwardly directed integral walls a³, are provided on the bottom a, of the float feed chamber and threaded 85 therein to close the same is the close fitting bottom a⁴, at the center of which is connected feed pipes a⁵. As shown also, a strainer a⁶, is secured on said bottom, and comprises, as shown, a plurality of plates of metal connected together and provided with apertures therethrough covered by wire gauze a⁷, to prevent any impurities or dirt in the gasoline finding its way into the float feed chamber.

Within the float feed chamber is provided 95 a float member of cork or constructed hollow of metal, and indicated by C. Threaded through the same is a spindle or stem c. The lower end of said spindle extends 100 through a relatively small aperture in the bottom of the float feed chamber and which flares outwardly on the under side and rigidly secured on the lower end of said stem is a ball c', which serves as the valve 105 closure. The upper end of said stem, as shown in Fig. 1, extends upwardly into a screw threaded nipple a⁸, at the center of the

cover, and which is closed by a centrally apertured screw cap a^8 , thus affording air inlet to the float feed chamber above the float.

- 5 Near the bottom of the float feed chamber is provided a bore b , which communicates with the passage b' leading into the mixing chamber B, and as shown, threaded into the inner wall of said mixing chamber and communicating in said passage, is a sleeve b^2 , which extends approximately to the middle of said mixing chamber and there receives the inwardly directed, slightly tapered end b^3 , of the inlet valve closure, which, as shown, is threaded through the side of the mixing chamber and is provided on its outer end with a graduated wheel B' , notched about its periphery and adapted to be engaged in any of said notches by a spring detent b^5 , and whereby said valve closure may be held in any of its adjusted positions.

Extending through the mixing chamber below the valve, is a threaded rod or bolt D, and supported thereon is a cup d, positioned directly beneath the discharge from the valve and provided around its periphery at the bottom with a plurality of apertures to permit the escape of the hydro-carbon fluid therefrom, and supported on the bottom of said cup is a cage D', which may be constructed of wires, which are somewhat spherically and downwardly curved to distribute the inwardly flowing gasoline or hydro-carbon over as large a vaporizing area as possible within the mixing chamber. Said cage may, of course, be constructed of stamped metal, if desired, to afford a plurality of rods or surfaces down which the hydro-carbon flows as the air passes inwardly therethrough.

At the lower or outlet end of the mixing chamber is provided a throttle valve. This is shown as the ordinary butterfly valve comprising plates of metal riveted or otherwise secured together upon a stem e, and affording the closure E. Said stem, as shown, extends inwardly through suitable diametrically arranged apertures in the lower end of the mixing chamber, and as shown, said stem on its outer end is provided with a bell crank e' , whereby the throttle valve may be actuated by any suitable connection.

Conveniently and preferably, the lower or outlet end of the mixing chamber is provided with two sets of apertures arranged at right angles with each other to enable the stem or pivot for the butterfly valve to be adjusted most conveniently with reference to the installation of the carburetor in use. The apertures not required are closed by screw plugs e^3 , said screw plugs being adapted to fit within any of said apertures when the closure, stem or pintle is engaged in the others.

The air valve may be constructed in a va-

riety of ways. Conveniently, however, a spider F, is threaded upon the upper open end of the mixing chamber and is flanged downwardly at its periphery and screw threaded to receive the complementally threaded lower edge of the cap or casing F'. As shown, a cylindric sleeve f, is provided integral with said spider F, at the axis thereof and is of a length to project above the open end of the casing and is provided thereon with a centrally apertured screw cap f' , and slideable on said sleeve is an air valve closure f^3 , which seats to close the aperture in the casing F', under the action of a spring f^4 , which engages on said spider and underneath the closure acts to force the same upwardly against the intake of the engine.

In the construction shown in Fig. 1, the gasoline supply is received from below the float feed chamber. The inlet may as conveniently be received from above the same, and for this purpose, as shown in Figs. 9 and 10, the cover A², for the float feed chamber, may be provided with a central axially apertured boss thereon, internally threaded and in which is threaded an upwardly extending sleeve G, provided in its bottom with a relatively small aperture, which flares downwardly to afford a seat for a ball g, carried on the stem g', of the float G'. As shown, an apertured screw cap g², fitted into the upper end of the sleeve G, and also said sleeve G, is provided with a laterally apertured branch g³, adapted to afford connection with the gasoline supply pipe, thus discharging the gasoline from the supply pipe directly into the float feed chamber from above. All of the other parts of the construction may be as before described.

The operation is as follows: With either construction of the float feed chamber the ball valve under the action of the float and because of the buoyancy of the float, serves to perfectly regulate the supply of gasoline in the float feed chamber to the needs of the motor, always maintaining a sufficient level of gasoline in the float feed chamber to supply the combustion, but obviously preventing any excess finding its way thereto. However, if desired, an orifice may be provided at the normal level of the liquid in the float feed chamber, and may be closed by means of a screw g⁷, to enable the contents of the float feed chamber to be discharged to normal level should it by any possibility flood, as, for instance, by parts sticking of the valve. This, however, can never occur except when the ball valve has practically worn out, and, owing to the construction the ball may be renewed at any time, thus enabling a carburetor to work as satisfactorily in this respect as before. As the gasoline or other explosive fluid is

drawn through the bore b , and into the sleeve b^2 , of the valve, it is discharged in amounts requisite for the combustion into the cup d , and at the top of the mixing cage, 5 from whence it escapes from the apertures in the bottom of the cup and flows down over the mixing cage subjected in its downward flow to the action of the indrawn atmospheric air, which passes through the 10 cage and to the motor carrying the perfectly vaporized hydro-carbon thoroughly mixed therewith.

Should it be desired to graduate the action of the valve to secure a greater or a less 15 flow of the gasoline or other fluid, this may be accomplished by the graduated head B' , of the valve closure, and when adjusted the spring detent b^5 , will hold the valve at all times in adjusted position.

20 Of course, under normal action of the carbureter, the air valve is drawn automatically inward by the suction of the intake of the motor. However, a sufficient supply of air may be provided at any time through the 25 apertured cap for the tubular stem of the air valve to maintain the combustion at a less rate of speed.

Of course, it is quite immaterial if the 30 flow of the hydro-carbon to the float feed chamber be from above or from below. In any event, the float acts to perfectly regulate the supply, and as the same is discharged to the mixing chamber, the float again falls to permit an inflow for the next charge.

35 While I have described my invention with reference to a spherical float valve, it is not to be understood that this type of float valve is indispensable to the operation of this device, or that I purpose limiting myself 40 thereby. Instead, this and many other details of the construction may be varied without departing from the principles of my invention. I therefore do not purpose limiting this application for patent otherwise 45 than necessitated by the prior art.

I claim as my invention:

1. The combination with a float feed chamber connected with a source of hydro-carbon fluid supply, of a mixing chamber regulably 50 connected therewith through a suitable part, a cup in the mixing chamber to receive the discharge from the float feed chamber, and a mixing cage supported below the cup comprising a plurality of wires spherically curved upon which the cup discharges through apertures in its bottom.

2. The combination with a float feed chamber connected with a source of hydro-carbon fluid supply, of a mixing chamber regulably 60 connected therewith, a cup in the mixing chamber positioned to receive the discharge from the float feed chamber, and a mixing cage supported below the cup comprising a member stamped to provide flat bars which 65 are curved to afford large surface on which

the cup discharges through apertures in its bottom.

3. The combination with a float feed chamber connected with a source of hydro-carbon fluid supply, of a mixing chamber regulably 70 communicating therewith, a cup centrally positioned in the mixing chamber to receive the discharge from the float feed chamber, a mixing cage supported below the cup and to which the latter discharges through apertures in its bottom, said cage affording downwardly directed curved bars adapted to afford a large vaporizing area for the hydro-carbon fluid in the path of air drawn through the mixing cage. 75

4. In a device of the class described a cup having apertures in its bottom, and arranged to receive the flow from the hydro-carbon feed chamber, a mixing cage of flat metallic bars curved somewhat spherically and secured to the cup to receive the flow of the hydrocarbon thereon from the cup, said device having an air inlet orifice above and a discharge orifice below the mixing cage. 80

5. In a device of the class described the 90 combination with a float feed chamber and a mixing chamber, of a passage connecting the same, an inlet valve controlling the said passage, a threaded shaft extending transversely through the mixing chamber, a cup 95 threaded on said shaft in the mixing chamber to receive the hydro-carbon from said passage, and a globular mixing cage supported below said cup and adapted to be bathed by the flow of the hydro-carbon 100 through apertures in the bottom of the cup, said cage being disposed between the air inlet aperture and the outlet for the mixing chamber.

6. A carbureter comprising a feed chamber, a mixing chamber communicating therewith, a cup in the mixing chamber to receive the liquid therein from the feed chamber and finely apertured to spray the liquid therefrom, a mixing member comprising independent metallic members on which the sprayed liquid falls, a sleeve opening into the mixing chamber above the mixing member, a cap for the mixing chamber having a large opening around the sleeve and a spring 110 pressed closure for closing the opening around the sleeve. 115

7. In a device of the class described a mixing chamber ported to connect with the bottom of the float feed chamber, and a globular mixing cage therein constructed of a plate stamped to provide narrow flat bars with slits therebetween and said bars curved to provide a surface over which the hydro-carbon spreads, said cage being in the path 120 of the air intake. 125

8. In a device of the class described a mixing chamber ported to connect with the float feed chamber, a globular mixing cage in the mixing chamber in the path of the air 130

intake, an inlet pipe extending transversely into the mixing chamber, a closure extending transversely of the chamber adapted to control the admission through the inlet pipe, a
5 stem extending parallel of the inlet pipe and a cup threaded therein adapted to spray the hydro-carbon fluid upon the mixing cage.

In testimony whereof I have hereunto subscribed my name in the presence of two subscribing witnesses.

FREDERICK W. TUERK.
